RESTAURANT BUILDING

Charles Weinstein, Outer Pierrepont Ave.,
Potsdam, N.Y.

Filed July 17, 1961, Ser. No. 65,956

Term of patent 14 years

(Cl. D13—1)

FIG. 1

The appearance of the opposite side of the building is substantially similar to the side shown in FIG. 1.

I claim:

The ornamental design for a restaurant building, as shown and described.
